UNITED STATES PATENT OFFICE.

MATHIAS CHARLES THEISEN, OF DIANA, DAKOTA TERRITORY.

HARROW.

SPECIFICATION forming part of Letters Patent No. 352,279, dated November 9, 1886.

Application filed May 18, 1886. Serial No. 202,541. (No model.)

To all whom it may concern:

Be it known that I, MATHIAS CHARLES THEISEN, of Diana, in the county of Sanborn and Territory of Dakota, have invented a new 5 and useful Improvement in Harrows, of which the following is a full, clear, and exact description.

Reference is to be had to the accompanying drawings, forming a part of this specification, 10 in which similar letters of reference indicate corresponding parts in all the figures.

Figure 1 is a plan view of a part of a harrow to which my improvement has been applied, arranged to give a flexible joint. Fig. 15 2 is a sectional elevation of the same. Fig. 3 is a plan view of a part of the same, arranged to give a rigid joint. Fig. 4 is a side elevation of a part of a coupling-bar, partly in section, and shown locked. Fig. 5 is an elevation 20 of a harrow-tooth.

The object of this invention is to provide harrows constructed in such a manner that they can be readily adjusted for use as a rigid harrow, a flexible harrow, a smoothing-harrow, or a straight-tooth harrow, and which 25 shall be simple in construction and strong and durable in use.

The invention consists in the construction and combination of various parts of the harrow, as will be hereinafter fully described.

A represents the tooth-bars of the harrow. The tooth-bars A are connected to form the harrow-sections by iron bars B, which are made with upward bends to receive and fit 35 upon the top and opposite sides of the tooth-bars A. The bends of the coupling-bars B are made of such a depth that the lower surfaces of the parts of the said coupling-bars B between the tooth-bars A will be flush with 40 the bottoms of the said tooth-bars A.

The coupling-bars B are secured to the tooth-bars A by bolts C, passing through the bends of the said coupling-bars and through the said tooth-bars as near the bottoms of the 45 said tooth-bars as is practicable. The coupling-bars B are jointed between the adjacent tooth-bars A to make the harrow-sections flexible. One end of the parts of a bar, B, forming a joint has a long slot formed in it, 50 and is provided with an eye at the ends of its prongs to receive the hinging-pin D, which

also passes through an eye in the other part of the said bar at the base of its tongue, the said tongue being made of such a length and size as to fit into the slot in the other end, so 55 that the joint will have a free vertical movement, but no lateral movement.

To the upper and lower sides of the slotted part of the bar B, at the inner end of its slot, are secured by a bolt, E, two buttons, F, which 60 have lips G at one end, to engage with the bar B and prevent the said buttons from turning upon the said bar B. When the buttons F are arranged across the bar B, as shown in Figs. 1 and 2, the tongue will be free to play 65 in its slot. When the buttons F are arranged longitudinally with the bar B, as shown in Figs. 3 and 4, the inner ends of the said buttons overlap the upper and lower sides of the end of the tongue and make the joint rigid. 70 In this case a hole, H, is formed in the bar B at a little distance from the bolt-hole to receive the lips G, so that the said buttons will be held from turning. The bolt E is provided with a nut, I, and a jam-nut, J, to hold the 75 said bolt from working loose. With this construction the harrow-sections can be made flexible or rigid, as the work to be done may require.

The bars A are perforated to receive the 80 teeth K, which are made of steel. The upper parts of the teeth K are made square, and their lower parts are tapered upon two adjacent sides, leaving one edge of the said teeth straight from end to end. The teeth K are 85 inserted in the bars A, with their straight edges toward the same side of the harrow, so that when the draft is applied to that side of the said harrow the harrow will operate as a straight-tooth harrow, but when the draft is 90 applied to the other side of the harrow the said harrow will operate as a smoothing-harrow.

Having thus fully described my invention, I claim as new and desire to secure by Letters 95 Patent—

1. The herein-described coupling for harrows, consisting of the bars B, each provided with a bend for receiving the tooth-bars, and one formed with a slot and the other with a 100 tongue pivoted in said slot at the ends of its prongs, and buttons pivoted to one bar for

locking the free end of the tongue in the slot, as set forth.

2. In a harrow, the combination, with the tooth-bars A and the coupling-bars B, having hinge-joints, of the buttons F, having lips G, and the fastening-bolts E and nuts I J, substantially as herein shown and described,

whereby the hinge-joints of the coupling-bars can be made rigid, as set forth.

MATHIAS CHARLES THEISEN.
